UNITED STATES PATENT OFFICE

GEORGE RICKS, OF TUSCUMBIA, ALABAMA.

QUILTING-FRAME.

1,115,573.

Specification of Letters Patent.

Patented Nov. 3, 1914.

Application filed September 17, 1913. Serial No. 790,247.

To all whom it may concern:

Be it known that I, GEORGE RICKS, a citizen of the United States, residing at Tus-
cumbia, in the county of Colbert and State
5 of Alabama, have invented a new and use-
ful Quilting-Frame; and I do hereby declare
the following to be a full, clear, and exact
description of the invention, such as will en-
able others skilled in the art to which it ap-
10 pertains to make and use the same.

This invention relates to a new and use-
ful quilting frame.

As an object of the invention it is the aim
15 to provide a device of this nature, for fa-
cilitating the construction of quilts and the
like, for instance, a frame is provided where-
by a plurality of persons may assume posi-
tions about the frame, in order to conven-
20 iently reach the quilt, so as to readily take
part in the construction of the same, there-
by consuming considerable less time in com-
pleting a quilt. The quilt may be constructed
in great lengths, and then the required sec-
25 tions severed from the quilted material, and
the severed ends hemmed or otherwise
bound, to provide a finished edge for each
quilt.

Another object of the invention is to pro-
vide rollers, whereby the long lengths of
30 quilted material, as completed, may be
rolled from one roller to another.

Another object is to provide means ver-
tically adjustable, for raising the central
35 portion of the quilt, so that it is rendered
easier and more convenient for the persons
to reach different portions of the quilt, so
as to execute the required sewing or stitch-
ing.

In practical fields the details of construc-
40 tion may necessitate alterations, to which
the patentee is entitled, provided the altera-
tions fall within the scope of what is
claimed.

The invention comprises further features
45 and combination of parts, as hereinafter set
forth, shown in the drawings and claimed.

In the drawings: Figure 1 is a view in
side elevation of the improved quilting
50 frame constructed in accordance with the
invention. Fig. 2 is a plan view. Fig. 3 is
a sectional view on line 3—3 of Fig. 1. Fig.
4 is a sectional view on line 4—4 of Fig. 2.
Fig. 5 is a view partly in section and partly
55 in elevation, showing a portion of the shaft
8, the gear member 21°, the spring device 18,
the crank 17, and the parts 25, 26, 27, 28 and

35, and other detail features. Fig. 6 is a de-
tail perspective view of a portion of the
quilting frame, showing a portion of the
adjustable means for raising and lowering 60
substantially the central portion of the
quilt.

Referring more particularly to the draw-
ings, 1 and 2 designate two horizontally dis-
posed parallel bars. Each end of each bar 65
is provided with mortised recesses 3, in
which the upper ends of the legs 4 are bolt-
ed, by means of the bolts 5.

Adjacent the legs 4 the bars 1 and 2 are
provided with slots 6, which extend toward 70
one another and downwardly, that is, in
each respective bar. These slots 6 act as
bearings for the cylindrical portions 7 of
the shafts 8 and 9, which in cross section are
rectangular, so as to prevent the material 75
(which is wound or rolled about the shafts
from slipping) and while the quilt 10 is
thereon the same is adapted to be stitched.
Pivoted at 12 to the bars 1 and 2 are latch
members 13 having rectangular notches 14 80
to engage the rectangular shafts to prevent
them from turning, that is, while construct-
ing the quilt. After that portion of the ma-
terial on which the quilt is constructed or
stitched has been covered with the quilted 85
material, the latch levers 13 may be raised,
thereby leaving the shafts free to be rotated,
by the cranks 16 and 17. However, only
the shaft 9 may need to be rotated by its
crank, for the reason that the quilt, or the 90
material on which the quilt is constructed
may be pulled or unreeled from the shaft 8.
To prevent the shaft 8 from unreeling too
quickly, a spring device 18 secured to the
block 19 of the bar 2, is provided with a 95
triangular portion 21, to yieldably engage
between the teeth of the gear member 21°,
in order to retard its rotation when unreel-
ing the quilt. The block 19 is pivotally
mounted, and is held yieldably in position 100
by the tail end 22 of the spring device 18
engaging the lug 22^a.

The inner faces of the bars 1 and 2 are
provided with guide recesses 23, the guide
walls 24 of which are inclined toward one 105
another. Dove-tailed in the guide recesses
23 so as to slide therein, are the standards
25, the lower portions of which terminate
in spring legs 26. These legs are adapted to
spring apart, so as to frictionally and yield-
ably engage the guide walls 24 of the guide
110 recesses, so as to offer slight resistance when

adjusting the standards 25, and to assist in holding the standards temporarily in adjusted positions, until the pins 27, which rest upon the lugs 28, are passed through 5 any two of the registering apertures 28^a of the spring legs, so as to firmly hold the standards 25 in adjusted positions. Mounted in bearings of the standards 25 are the spindles 30 of the roller 31, which extends 10 beneath the quilt. Removably mounted in the slot bearings 32 of the standards 25 are the spindles 33 of the roller or shaft 34, between which and the roller 31 the quilt is arranged. The roller 34 acts as means to 15 prevent the quilt from ruffling. In other words, holds the quilt straight and even. The pins or keys 27 are suspended from the standards 25, by small chains or cords 35, while a wire basket 36 is likewise suspended 20 from one of the standards 25, adapted to contain a ball of thread, used in stitching or constructing the quilt.

Each bar 1 and 2 is provided with apertures 38, in which a loop of heavy twine, 25 cord or the like, or any other suitable loop 39 is arranged. Each loop is provided with a pair of wire hooks 40, designed to engage the quilt, or the material on which the quilt is constructed, to hold the same 30 stretched, in order to render it easier and more convenient to stitch the various pieces forming a quilt in place. Pegs 41 extend through the apertures 38, to hold the loops adjusted.

35 By raising and lowering the standard 25, a substantially central portion of the quilt, may be raised or lowered, in order to ren-

der it more convenient for the person working upon the quilt, to reach various parts of the same, without undue strain or reaching.

From the foregoing, it is apparent that there has been devised an efficient, simple construction of quilting frame, and one which has been found desirable and practical.

The invention having been set forth, what is claimed as new and useful is:—

A quilting frame comprising a frame; revoluble means in the ends of said frame 50 for moving a quilt from one end of the frame to the other as it is completed; the sides of the frame upon their inner adjacent faces having dove-tailed guides, standards having spring legs provided with registering apertures dove-tailed in said guides, rollers mounted in said standards and between which the quilt is arranged, the inner face of each side of said frame having headed lugs, a pair upon each side 55 of the dove-tailed guides, and a key pin anchored to each side of the frame and passing between said pairs of headed lugs and passing through selected apertures of said spring legs for holding the standards in vertical adjusted positions.

In testimony whereof I have signed my name to this specification in the presence of two subscribing witnesses.

GEORGE RICKS.
